THERMOSTATICALLY CONTROLLED DAMPER MECHANISM FOR RADIATORS

Filed Dec. 28. 1922

UNITED STATES PATENT OFFICE.

ERNEST W. SEAHOLM, OF DETROIT, MICHIGAN, ASSIGNOR TO GENERAL MOTORS CORPORATION, OF DETROIT, MICHIGAN, A CORPORATION OF DELAWARE.

THERMOSTATICALLY-CONTROLLED DAMPER MECHANISM FOR RADIATORS.

Application filed December 28, 1922. Serial No. 609,434.

My invention relates to radiator mechanism for use in connection with internal combustion engines employed for operating motor driven vehicles and for similar purposes; and particularly to radiator mechanism in which means, commonly in the form of a plurality of shutters, dampers or vanes are employed for the purpose of controlling the flow of air through the cellular structure 10 of the radiator and past the tubes or plates whereby the cooling liquid flowing therethrough is divided into a plurality of comparatively thin streams to more effectively accomplish the cooling thereof.

15 The principal object of my invention is to provide an improved radiator mechanism wherein the flow of air which accomplishes the cooling of the water is controlled by shutters, dampers or equivalent devices; and 20 in which the operation of the shutters is controlled by a thermostat so located as to be affected by the temperature of the engine with which the radiator is used, so that the flow of air through the radiator will be dependent upon and will vary with the temperature of the engine with which the radiator is used.

25 A further object of my invention is to provide a radiator system of the class or type referred to and wherein the arrangement of the parts and their action is such that the flow of air through the radiator will be arrested when the engine is cold, and permitted to occur when the engine is in a heated condition; the control of the said air flow controlling means being accomplished by a thermostat so located as to be heated by the cooling water within the radiator itself; this result being preferably attained by locating 30 the thermostat in a chamber arranged within the upper liquid chamber of the radiator where the temperature of the cooling water is the highest. In carrying out the ideas of my invention as above expressed the shutters, dampers, or other air flow controlling means are operated by air compressed by a pump operated by the engine; the action of the air to accomplish the movement of the air flow controlling means being controlled 40 by a thermostat for the purpose hereinbefore explained.

45 A further object of my invention is to provide improved mechanism operated by air

pressure and controlled by a thermostat for operating dampers or shutters located in front of the radiator and adapted to control the flow of air through the cellular intermediate portion thereof, the device being simple in construction and made up of few parts so that it may be manufactured at a minimum of expense and will at the same time be effective and efficient for the purpose for which it is provided.

55 With the above and other objects of invention in view my invention consists in the improved radiator shutter or damper operating mechanism illustrated in the accompanying drawings and hereinafter described and explained; and in such variations and modifications thereof, within the scope of the concluding claim, as will be obvious to those skilled in the art to which my invention relates.

60 Referring now to the drawing wherein the preferred embodiment of my invention is illustrated:

65 Figure 1 is a view showing an engine having a radiator equipped with my invention.

70 Figure 2 is a fragmentary view upon a considerably larger scale illustrating the principal parts and features of my invention.

75 Referring to the drawing, the reference numeral 3 designates an internal combustion engine of the multiple cylinder type or variety, and which is assumed to be used in driving a motor driven vehicle; the engine being equipped with a radiator comprising upper and lower water chambers 4, 5, between which the cellular water cooling section or structure 6 is located, and downward through which the cooling water flows. This cellular portion of the radiator may be of any form whereby the downwardly flowing water is divided into a large number of 80 comparatively thin streams to thereby accomplish the cooling thereof the more effectively. The upper water chamber is connected with the upper end of the water jacket of the engine through a conduit 7, 85 and water from the lower chamber 5 returns to the water jacket through a conduit 8 as is usual in cooling systems of internal combustion engines.

90 Located in front of the radiator or rather in front of the intermediate cellular portion

105

6 thereof are a plurality of oscillating vanes or shutters 9 which collectively provide means for controlling the flow of air through the radiator and past the water passages thereof; said shutters being shown as provided with trunnions 10 at their ends, which are supported in bearings in two oppositely disposed flanges 11 which in turn are carried by and formed as parts of the 10 enclosing casing 12, commonly provided for covering the radiator and giving it a more artistic appearance. These shutters or dampers are provided with arms 13 all of which are pivotally connected with a vertically disposed rod 14, so that as said rod is moved up and down all the shutters will be operated in unison. Figure 1 shows the vanes as in their closed positions, with their upper and lower edges fitting closely 20 throughout the series so as to substantially arrest the flow of air through the radiator; while Figure 2 shows in dotted lines these shutters as open so as to permit air to flow past them and through the radiator structure.

The rod 14 and the air flow controlling device provided by the shutters is operated by an air operated member which, while it may assume a variety of forms, is illustrated as made up of a corrugated expandable and contractable chamber 15 having a lower movable wall 16 which is pivotally connected with the upper end of said rod; and the reference numeral 17 designates a 30 suitable pump supported from the crank case of the engine in the embodiment of my invention illustrated, and operated from the engine through suitable gears, or otherwise, in accordance with the choice of the designer having in mind the particular motor vehicle power plant with which my invention is to be used. The cylinder of this pump is connected with the interior of the chamber 15 through a conduit 18, so that air compressed by the pump may flow to said chamber and accomplish the operation of the shutters as above explained; it being obvious that when the air compressed by the pump is permitted to act with full force within 40 the chamber 15 the wall 16 will be depressed and the shutters opened. If, however, the air discharged from the pump is not permitted to act within the chamber 15 then and in that event the shutters will remain 50 in their closed position even though the pump may be in operation, the shutters being moved into and held in such closed position by a spring 19 acting upwardly against the lower end of the rod 14, and against the 60 resistance of which spring said rod is depressed when air compressed by the pump is permitted to act with full force within the said chamber 15.

In order to control the action of the air 65 compressed by the pump to accomplish the

results hereinbefore mentioned the conduit 18 is provided with a branch conduit or connection 20 leading to the external atmosphere, and the flow through said bypass is controlled by a thermostat the operation of which is dependent upon engine temperature. Such a thermostat is shown at 21, the thermostat illustrated being of the bimetal strip type and the same having a valve 22 at its free end adapted to close over the 70 end of the branch conduit 20 above referred to. The thermostat is preferably so arranged that it will be exposed to as near the temperature at which the engine is operating as possible, to which end the same is located within a chamber 23 provided in or adjacent the upper water chamber 4 of the radiator and into which the cooling water is returned at or near the highest 80 temperature which it reaches, and at a temperature not greatly below the temperature at which the engine will operate the most efficiently. This thermostat is illustrated as carried by a cover 24 which closes the open outer side of the chamber 23; and the branch 90 conduit 20 is shown as threaded, and as provided with an adjusting nut 25 and lock nut 26, whereby the free or discharge end of said conduit may be adjusted relative to the valve 22 and to the thermostat 21 to thereby secure a proper operation of the system as a whole.

The thermostat 21 is so arranged that when the engine is cold or after it has remained idle for some time the valve 22 will stand away from the open end of the branch conduit 20; from which it follows that when the engine is started, and notwithstanding the air pump 17 is in operation, the shutters will remain in their closed position and will act to prevent a flow of air through the cellular structure of the radiator; because the air which is being forced through the conduit 18 by the pump is free to flow from the conduit through the passage 20 and into the chamber 23, and from said chamber through an opening 27 into the external atmosphere. As the engine becomes heated, however, the temperature within the chamber 23 will rise because of the rising temperature of the water discharged into the upper radiator chamber 4 and, after the engine has been in operation for a short time, the thermostat will act to move the valve 22 into a closed position over and upon the end of the branch conduit 20. As the valve approaches the seat provided by the end of said branch conduit the flow of air from said conduit into the chamber 23 will be gradually reduced, and finally arrested, such action being followed by increasing pressure within the expandable chamber 15 and by a concomitant opening movement of the shutters 9. The position of the valve 22 will obviously depend upon the temperature of the 100 105 110 115 120 125 130

engine from which it follows that while the shutters will generally be either fully open or fully closed they will nevertheless, especially if the engine operates for a considerable time below its maximum capacity, assume a position in which they are part way open only; thus reducing the flow of air without entirely arresting it and permitting the engine to regain the higher temperature at which it should operate. When the engine stops the temperature within the chamber 23 will fall and the thermostat will permit air to escape from the conduit 18 thus bringing about a prompt closing of the shutters, which will prevent the cooling of the radiator while the engine remains out of operation. As a matter of fact there will ordinarily be some little leakage through the branch conduit 20 and past the valve 22 even when the engine is operated at its maximum temperature, so that the closing action of the shutters occurs without delay, and substantially simultaneously with the cessation of operation of the engine and of the air pump; and access of air to the cellular structure of the radiator is prevented so long as the engine remains at rest, thus avoiding the waste incident to the cooling action of the atmosphere upon the radiator when the engine is stopped.

Having thus described and explained my

invention, I claim and desire to secure by Letters Patent:

In a device of the class described and in combination with an internal combustion engine, an air pump separate and independent of the engine and operated thereby, a radiator having an upper water chamber and a cellular structure below said chamber, and means for controlling the flow of air past or through said cellular structure; an air operated member operatively connected with said air flow controlling means; a conduit connecting said pump with said air operated member; a thermostat chamber located within said upper water chamber, and which thermostat chamber is open at one side; a cover for closing the open side of said thermostat chamber, and which cover is provided with an opening through which said chamber is placed in communication with the external atmosphere; a by-pass passage leading from said conduit through said cover and discharging into said thermostat chamber; a valve for controlling the flow through said by-pass passage; and a thermostat carried by said cover and located within said thermostat chamber, and which thermostat is operatively connected with said valve.

In testimony whereof I affix my signature.

ERNEST W. SEAHOLM.
